UNITED STATES PATENT OFFICE.

MORRIS LEVITAN, OF NEW YORK, N. Y.

DESIGN FOR AN ELECTRIC-LIGHTING FIXTURE FOR CEILINGS.

Application filed September 28, 1925. Serial No. 14,923. Term of patent $3\frac{1}{2}$ years.

To all whom it may concern:

Be it known that I, MORRIS LEVITAN, a citizen of the United States, residing at No. 868 Faile Street, borough of Bronx, city and State of New York, have invented a new, original, and ornamental Design for an Electric-Lighting Fixture for Ceilings, of which the following is a specification, reference be-

ing had to the accompanying drawing, forming a part thereof.

The figure shows a perspective view of my design for electric-lighting fixtures.

I claim:

The ornamental design for an electric-lighting fixture for ceilings as shown.

MORRIS LEVITAN.
